AUTOMATIC CONTROL FOR REVERSING
PROPELLERS

Melvin E. Longfellow, Manchester, Conn., assignor to United Aircraft Corporation, East Hartford, Conn., a corporation of Delaware

Application November 26, 1946, Serial No. 712,402

14 Claims. (Cl. 170—160.2)

1

This invention relates to hydro-controllable propellers of the type which may be feathered or reversed and particularly to improved control mechanism operative during unreversing of the propeller blades.

In propellers having a high rate of pitch change some automatic, quick-acting means must be provided to insure the return of the propeller to the governor controlled, constant speed range when the propeller is unreversed. Otherwise the blades will be positioned against the high pitch constant speed range stop before their release to constant speed operation.

It is an object of this invention to provide improved means, operative during unreversing of the propeller for automatically returning the propeller to the constant-speed, governor-controlled range.

Another object of the invention is the provision of electrically operated means for automatically returning the propeller to a governor control at a predetermined pitch setting during unreversing.

A further object of this invention is generally to improve the construction and operation of feathering and reversing propellers.

These and other objects and advantages of the invention will be apparent from the specification and claims and from the accompanying drawings which show what is now considered to be a preferred embodiment of the invention.

In these drawings:

Fig. 1 is a diagrammatic view of the pitch control means of a hydraulically actuated, constant speed, feathering and reversing propeller embodying the invention;

Fig. 2 is a longitudinal sectional view through the pitch limit mechanism;

Fig. 3 is a sectional view of lines 3—3 of Figure 2.

Referring to the drawings in detail and particularly to Fig. 1, the numeral 10 generally indicates a hydro-controllable feathering-type propeller having a hub 11, and the numeral 12 generally indicates the propeller driving engine from which the propeller drive shaft, generally indicated at 14, projects. The propeller 10 is provided with suitable pitch changing apparatus and is shown herein as having an individual vane type hydraulic motor for each blade, one of such motors being shown diagrammatically in section in Fig. 1 and generally indicated at 16. Each motor has an outer movable portion 18 connected to the corresponding propeller blade and provided with two diametrically opposed vanes 20

2

and 22 and an inner fixed member 24 provided with two diametrically opposed vanes 26 and 28. Fluid is supplied to the pitch changing motors of the several blades from a suitable pressure source, such as the pump generally indicated at 30, rotatable with engine driven shaft 14, and having piston plungers 31 reciprocated by a normally relatively fixed cam 33. From pump 30 fluid is conducted through the pressure conduits 10 32 leading to the distributing valve generally indicated at 34, and from the distributing valve selectively to the conduits 36 and 38, depending upon the setting of the valve as positioned by the governor to determine the direction of propeller pitch change. When hydraulic fluid under pressure is supplied through one of the lines 36 or 38 to one side of the pitch changing motors, fluid will drain from the opposite side of the motors through the other line to valve 34 from 15 which it will be conducted through the conduit 40 to the sump, or reservoir, 42 connected with the intake side of pump 30. The pump 30 and the sump 42 are located in the propeller hub and the pump plungers 31 are reciprocated during 20 rotation of the propeller by rotation around stationary cam 33.

The fluid distributing valve 34 is also located in the propeller hub and rotates therewith. This valve is controlled by a speed responsive governor 30 generally indicated at 43 driven from the engine 12 by a suitable gear drive including a gear 44 on the governor drive shaft 45 and a gear 46 concentric with and rotatable with shaft 14, as shown in the diagrammatic showing of Fig. 1. The governor 43 includes a set of centrifugally actuated fly balls 48 which act to move a slide valve 50 in opposition to a speeder spring 52. The slide valve 50 reciprocates in a fixed valve cylinder 54, and the side walls of the valve and valve cylinder are provided with registering ports in a usual manner which control the flow of fluid through the governor. A fluid pump 56, shown herein as of the gear type, is driven from governor drive shaft 45 and supplies pressure fluid from 35 reservoir 60 through conduit 62, constant pressure valve 64 and conduit 66 to the governor which, when its ports are aligned, admits high pressure fluid to conduit 68, normally open solenoid operated valve A, conduits 70 and 72 to the servo-motor 74. Servo-motor 74 operates a piston rod 76 connected through the displacement mechanism 78 and rotational slip joint 80 with the plunger 82 of the pitch controlling, fluid distributing valve 34 so that the latter valve will 40 be positioned to change the pitch of the propeller.

propeller in response to demands by the governor for increase or decrease in the speed of engine 12 and its connected propeller.

Within the slide valve 50 there is a reciprocable pilot valve 90 projecting out of the upper end of the slide valve and connected to the end of a lever 92. Lever 92 is pivoted intermediate its length on a fixed pivot 94 and is pivotally connected at its other end to the upper end of a compensating plunger 96. At its lower end the pilot valve 90 carries a piston which controls the fluid flow through the governor ports to prevent over-travel of the governor in a well known manner.

Servo-motor 74 comprises a cylinder 98 in which a piston 100 reciprocates and a communicating cylinder 102 of reduced diameter in which an enlarged portion 104 of rod 76 reciprocates. This arrangement provides chambers 106 and 108 on the opposite sides of piston 100 having differential piston areas. Piston rod 76 extends into a cylindrical casing 109 and carries therein an abutment 110 which bears against one end of two concentric compression springs 111 and 112 (Fig. 3), the opposite ends of which bear against the closed end of the casing. Springs 111 and 112 thus oppose the action of the fluid under pressure in chamber 106 and constantly urge the piston rod 76 toward the left as viewed in Fig. 1.

Flow of high pressure fluid from the governor 43 through conduits 68, 70, and 72 to chamber 106 is controlled by normally open lock pitch solenoid valve A. Chamber 108 is connected by a conduit 114 with the bottom of cylinder 116 within which the compensating plunger 95 reciprocates. With this arrangement the pilot valve 90 as controlled by the compensator gradually retards the movement of the servo-motor as the propeller pitch approaches an angle corresponding to the speed change demand of the governor. The governor and compensator mechanism is more fully disclosed in a co-pending application, Serial No. 664,640, filed April 24, 1946, now abandoned, and assigned to the assignee of this application and reference is made thereto for a more complete understanding of this mechanism.

Chamber 106 is connected through conduit 72, manifold 118, a normally closed increase pitch solenoid valve C and conduit 119 with reservoir 60, this arrangement permitting fluid trapped in chamber 106 to be vented as piston 100 moves to the left in Fig. 1 under the action of springs 111 and 112 to increase the pitch of the blades.

Pressure fluid from pump 56 is also supplied through conduit 120, normally closed decrease pitch solenoid B, manifold 118, and conduit 72 to chamber 106 where it acts on piston 100 to move the blades toward low pitch position.

The valve 34 for distributing fluid to the vane motor has an outer cylindrical valve casing 121 provided with ports 122, 123, 124, 126, and 128. Within the casing 121 is a reciprocable sleeve 130 operatively connected at one of its ends with a propeller pitch changing mechanism by a suitable mechanical connection shown schematically in Fig. 1 as a bellcrank 132 and a cam 134 on the movable member 18 of pitch changing motor 16. The bellcrank is maintained in contact with the cam by a suitable compression spring 136. The valve plunger 82 extends into the sleeve 130 and is provided therein with spaced valve pistons 137 and 138 adapted to control ports provided in the valve sleeve 130 which are registerable respectively with ports 122, 123, 124, 126, and 128 in the outer valve casing 121 over the entire

range of relative movements between the sleeve and the casing. Port 123 is connected by conduit 38 with one side of the hydraulic motor 16. Port 126 is connected by conduit 36 with the other side of the hydraulic motor, and the port 124, located at the mid-length position of the distributor valve, is connected by conduits 144 and 32 with the outlet of the pump 30 so that fluid under pressure is supplied at all times when the propeller is rotating to this intermediate positioned port.

The operation of the distributing valve 34 is such that, when the plunger 82 is moved in response to the governor demands for a speed change, one side of the hydraulic motor 16 will be connected with the fluid under pressure entering from conduit 144 while the other side of the motor will be connected with the sump 42 through conduit 40, resulting in rotation of the motor 16 to change the propeller pitch. As the pitch is changed the sleeve 130 is moved to close off the connections between the distributing and the propeller pitch changing motor at a rate such that when the propeller pitch has been changed a number of degrees sufficient to correct the governor indicated deviation from the speed for which the governor is set, the pitch changing motor will be stopped and it will be hydraulically locked against any further pitch changing movement until servo-motor 74 again changes the position of plunger 82 in response to governor demands. Thus, the position of the servo-motor 74 and the plunger 82 always indicates the pitch angle of the propeller blades.

The above described mechanism provides an automatic constant speed control of the power plant over a predetermined range of propeller pitch angles, the limits of which is determined by a low pitch limit stop 146 and a high pitch limit stop 148 as shown diagrammatically in Fig. 1 and more in detail in Fig. 2. These stops are adjustably threaded on a hollow adjusting screw 150 which is slidably mounted on a shaft 152 mounted in the housing which supports cylinder 109. The adjusting screw 150 has a central squared portion over which two forked projections on the bottom of abutment 110 are received so that the screw 150 is reciprocated with piston rod 76. A pitch limit solenoid D is provided having a winding 154 and a core 156. The upper end of the core 156 carries a pin 158 which cooperates with two pivoted stop links 160 and 162 having abutment faces 164 and 166 that cooperate with stops 146 and 148. A light compression spring 168 constantly biases a plunger 169 upwardly into engagement with the core 156 and consequently biases the core and the abutment links 160 and 162 upwardly into stop engaging position. With the abutment links 160 and 162 in normal position shown in Fig. 2, in which the solenoid D is de-energized the reciprocating movements of the piston rod 76 are limited by engagement of the abutment 164 with the low pitch stop 146 on the one hand and engagement of abutment 166 with high pitch stop 148 on the other. This comprises the governor control, constant speed, or service, range of propeller blade angle variations.

At opposite extremes of the constant speed range of the servo-motor 74 special purpose ranges are provided into which the servo-motor may enter to feather the propeller blades at one extreme of travel and to reverse the pitch of the blades at the other extreme of travel. Thus when the solenoid D is energized and pulls the

stop links 160 and 162 down the travel of the piston rod 76 is then controlled by adjustable limit stops 170 and 172, which are mounted on rod 152 and are adjustably threaded into the casing. Of these the stop 170 comprises the feather stop and this is adjusted so that when the left-hand end of adjusting screw 150 (Fig. 2) engages the stop the servo-motor will have moved the propeller blades into feathered position. When the right-hand end of the adjusting screw 150 engages stop 172 the servo-motor will have moved the blades into full reverse pitch position.

In order to permit the servo-motor to move into these special purpose ranges, the solenoid D must be energized to withdraw the stop links 160, 162 from the constant speed range between the low pitch stop 146 and the high pitch stop 148. Upon the energization of solenoid D the plunger 169 is depressed against the action of spring 168 and closes a pair of contacts 174 carried by the solenoid housing, the purpose of which will be subsequently explained.

Up to this point the mechanism has been considered under conditions in which the propeller was rotating and the distributing valve 34 received pressure fluid from the pump 30 while the servo-motor received pressure fluid from the gear pump 56. Means are provided for adjusting the pitch of the propeller when the latter is not rotating, for example, when it is desired to unfeather a propeller previously feathered in flight or when the airplane is on the ground and the engine is not running and it is desired to operate the blade pitch changing motor. To this end a motor 176 is provided which drives the drum 178 through suitable beveled gears 180. The drum 178 carries a cam 192 which rocks a bell crank 184 pivoted at 186. The free end of the bell crank reciprocates a piston 188 of an auxiliary fluid pump which supplies fluid, received from the sump 60 through a conduit 189, to conduit 190 and manifold 118. During this operation the pump 30 is stationary and accordingly the rotation of drum 178 relative thereto will effect operation of plungers 31 to supply pressure fluid for operating the pitch changing motor 16.

Electrical means are provided for controlling the energization of the solenoid valves A, B, C and solenoid D as required to feather and unfeather the blades and also to reverse and unreverse the blades. The direction of movement of normally open solenoid valve A and normally closed solenoid valves B and C when energized is shown by arrows in Fig. 1. A manually operable push-pull switch 192 is provided for controlling the feathering and unfeathering operations which is normally biased into the position shown in Fig. 1 by compression springs 194 and 196 in which position its movable contact 198 is maintained out of contact with opposed sets of stationary contacts.

When it is desired to feather the propeller blades, switch 192 is pushed to the right in Fig. 1 to bridge the contacts 200, 202, 203, 204 and 206 by the movable switch member 198. This establishes the following circuits:

(1) A circuit from battery 208 through conductors 210, 212, contacts 200, 198, 203, conductor 214 and solenoid winding 216 of relay Z which closes its contacts to supply current from the battery to motor 176 through conductor 218 to start the auxiliary pump and main pump 30.

(2) A circuit from battery 208 through con-

ductors 210, 212, contacts 200, 198, 203, conductor 220, contacts 222 of the thermal timer unit, conductor 224 and holding coil 226 for manual switch 192, a shunt circuit also being established through the heating coil 228 of the thermal timer unit.

(3) A circuit from battery 208 through conductors 210, 212, contacts 200, 198, 204, conductors 230, 232, and 234, upper switch 236 of relay X to the winding of valve C.

(4) A circuit from battery 208 through conductors 210, 212, contacts 200, 198, 204, conductor 230, switch 238, of relay Y, conductor 240 and winding 154 of pitch limit solenoid D.

(5) A circuit from battery 208 through conductors 210, 212 contacts 200, 198, 206, conductors 242, 244 to the winding of valve A.

As a result of energizing valves A and C, solenoid D and the auxiliary motor 176, fluid from the governor 43 which is normally supplied through conduit 68 is cut off by the closing of valve A and the fluid which is trapped in chamber 106 is vented through conduit 72, manifold 118, open valve C and conduit 119 to the sump 60 under the action of springs 114 and 112 which move the servo-motor in a pitch increasing direction. Due to the energization of solenoid D, the stop links 160 and 162 are pulled down below the bottom of the high pitch limit stop 148, permitting the servo-motor to move into the feathered range in which the left-hand end of adjusting screw 150 engages the feather stop 170. The thermal timer unit is designed to open its contacts 222 after a predetermined time, for example 10 seconds, during which time the blade will have been moved to feathered position. Upon opening of the contacts 222 the switch 192 will return to its normal open position. The servo-motor will be in the feathered position of the blades and, since the pump 56 and auxiliary pump 188 are no longer in operation, the blades will remain in feathered position.

To unfeather the propeller the switch 192 is pulled to the left as viewed in Fig. 1 to bridge the contacts 246, 248, and 250. This establishes the following circuits:

(6) A circuit from battery 208 through conductors 210, 212, contacts 246, 198, 248, conductor 214, and solenoid coil 216 to close the contacts of relay Z and energize the auxiliary motor 176.

(7) A circuit from battery 208 through conductors 210, 212 contacts 246, 198, and 250, conductors 242 and 244 to energize the solenoid of valve A.

It will be evident that with solenoid valve A closed pressure fluid from the auxiliary pump supplied through conduit 190, manifold 118 and conduit 72 to chamber 106 will move the servo-motor in a direction to decrease the pitch of the propeller. In this operation the servo-motor will move in a pitch decreasing direction as long as the manual switch 192 is held closed. When the blades have been moved into the constant speed range, or as soon as the propeller starts to windmill, the switch 192 is released and the mechanism is returned to governor control. It will be evident from an inspection of Fig. 2 that when the servo-motor was in the blade feathered position the stop links 160, 162 were in a position to engage the periphery of the high pitch limit stop 148 so that in the subsequent unfeathering operation they were free to move without interference from this stop into the intermediate constant speed range.

To reverse the blades the reversing switch 252

is closed. This establishes the following circuits:

(8) A circuit from battery 208 through conductor 210, switch 252, conductors 256, 257, to solenoid of valve B.

(9) A circuit from battery 208 through conductors 210, 254, switch 252, conductors 256, 258, and coil 260 of relay X.

(10) This results in establishing a circuit from the battery 208 through conductors 210, 262, 264 and lower switch 266 of relay X (now in the dotted position), conductor 268 and coil 270 of relay Y.

(11) A circuit is also established from battery 208 through conductors 210, 262, 272, switch 274 of relay Y (now in dotted position), conductors 276, 234, switch 236 of relay X (now in dotted position), conductor 278 and coil of solenoid D.

(12) The closing of relay Y also establishes a circuit from battery 208 through conductors 210, 262, 272, switch 280 of relay Y (now in dotted position), conductors 282, 244 and solenoid of valve A.

(13) Closing of relay Y and depression of plunger 156 of solenoid D, also establishes a circuit from battery 208 through conductor 210, contacts 174, conductor 284, switch 286 of relay Y (now in dotted position), and coil 270 of relay Y which constitutes a holding circuit for relay Y independent of the above circuit (10).

High pressure fluid is now supplied from pump 56 through conduit 120, open solenoid valve B, manifold 118, and conduit 12 to chamber 106, thus moving the servo-motor in a pitch decreasing direction. Since solenoid D is also energized, the servo-motor can move the piston rod 76 in a low pitch direction into the special purpose or reverse pitch range until the end of adjusting screw 150 engages the reverse stop 172.

To unreverse the propeller blades it is only necessary to open switch 252 which de-energizes the circuit through coil 260 or relay X. Relay Y however remains energized through circuit (10) above. Contacts 174, which are in series in circuit (10), will remain closed, although the relay D is now de-energized because the stop links 160 and 162 are held down by the low pitch limit stop 146 the periphery of which overlies the free ends 288 of these links in the reverse pitch position of the servo-motor. Opening of relay X establishes

(14) A circuit from battery 208 through conductors 210, 262, 272, switch 274 of relay Y (which is in dotted position), conductors 276, 234 and switch 236 of relay X (now in full line position), to solenoid valve C. This permits the fluid in chamber 106 to be vented to the sump 60 as previously described and allows the servo-motor under the action of springs 111 and 112 to move in a pitch increasing direction. As the low pitch limit stop 146 moves off the links 160 and 162, the solenoid core 156 is moved upward by pin 169 under the action of spring 168 and contacts 174 are opened. This results in opening circuit (13) previously described through the coil 270 of relay Y which de-energizes solenoid valves A and C and allows the mechanism to return to its normal position with the abutments 164 and 166 in the constant speed range between stops 146 and 148.

Switch 283 is an independent control for the solenoid valve A and is used to lock the propeller in any pitch that it may happen to be in at the time the switch 283 is closed.

It will be evident that as a result of these improvements automatically operable means have

been provided for returning a propeller having a high rate of pitch change to governor controlled, constant speed range when the propeller is unreversed.

Further, means have been provided by this invention for automatically returning a propeller of this type to governor control at a predetermined pitch setting during unreversing.

While only one embodiment of the invention has been shown and described, it will be understood that various changes in the construction and arrangement of the parts may be made without departing from the scope of the invention as defined by the appended claims.

What is claimed as new is:

1. In combination with a propeller having controllable pitch blades, hydraulic means for controlling the pitch of the blades including a servomotor, cooperating fixed and movable stop means normally limiting the movements of said servomotor and defining the service range of the propeller, means operatively connecting said movable stop means with pitch controlling means for movement therewith, a constant speed governor controlling said servomotor throughout said range, a plurality of electrically actuated means connected with and controlling the operation of said servomotor and one of said stop means for disabling said stops and moving the propeller blades beyond said service range into reverse pitch, means for energizing a selected group of said electrically actuated means including said stop disabling means for reversing the propeller, means for energizing another selected group of said electrically actuated means for unreversing the propeller, switch means connected with said another selected group of electrically actuated means and with said one stop means and actuated by the return of said one stop means into position to cooperate with said other stop means for automatically deenergizing said another selected group of electrically actuated means and returning the propeller to governor operation and manually operable switch means controlling the operation of both of said energizing means.

2. In combination with a propeller having controllable pitch blades, hydraulic means for controlling the pitch of the blades including a servomotor, a governor and a plurality of electrically actuated valves controlling the operation of said servomotor including a lock pitch and governor disabling valve, a decrease pitch valve and an increase pitch valve, cooperating stop means preventing pitch changing movement of said servomotor beyond predetermined limits to define an intermediate service range of blade pitch variation, means operatively connecting at least a portion of said stop means with said pitch controlling means for movement therewith, electrical means for retracting one of said stop means out of cooperating position for conditioning said servomotor to move said blades into reverse pitch, means including a relay for energizing said electrically actuated lock pitch and governor disabling valve, said decrease pitch valve and said stop retracting means for disabling said governor control and said stop means and moving said servomotor into reverse pitch, a second relay having a holding coil circuit energized by the closing of said first relay, said second relay controlling the energization of said lock pitch and governor disabling solenoid and said increase pitch solenoid, means including a pair of contacts in the holding coil circuit of

said second relay normally biased into open position, and operatively connected with said one stop means for holding said contacts closed in the reverse pitch range and for automatically opening said contacts to de-energize said second relay as said servo-motor moves into said governor controlled range and said one stop returns to cooperating position.

3. In a controllable pitch propeller having a service range of pitch change and a special purpose range of pitch change beyond said service range, pitch changing mechanism, a control for said pitch changing mechanism, manually controlled means operatively connected with said control for setting said control for changing the pitch from said special purpose range to said service range, a mechanical pitch limit stop having cooperating relatively movable parts relatively movable with pitch changing movements of said propeller and dividing said ranges, manually controlled means for disabling said stop, means for automatically re-activating said stop incident to changing propeller pitch from the special purpose range to the service range, and means operatively connected with said stop and said manually controlled means maintaining said control in operative position while the pitch is changing from said special purpose range to said service range and means forming a part of said control automatically actuated responsive to re-activating action of said stop to automatically disable said control.

4. In a controllable pitch propeller having a service range of pitch change and a special purpose range of pitch change beyond said service range, pitch changing mechanism, a governor for controlling the propeller pitch within said service range, other means for controlling the propeller pitch outside of said service range including means for disabling control by said governor, means for automatically restoring control by said governor upon return of the propeller pitch from outside said service range to within said service range including a two part device having relatively movable parts and means operatively connected with said mechanism for relatively positioning said parts in accordance with propeller pitch, control means operatively connected with said device and actuated thereby responsive to movement of said parts past a pre-selected relative position, means operatively connected with said other means for disabling said other means, means operatively connecting said control means with both said disabling means to automatically disable said other means and restore control to said governor upon actuation of said control means.

5. In a controllable pitch propeller having a service range of pitch change and a special purpose range of pitch change beyond said service range, pitch changing mechanism, a governor for said mechanism, a first electrical means connected with said mechanism for controlling the propeller pitch outside of said service range and a second electrical means for disabling control by said governor, means for automatically restoring control by said governor upon return of the propeller pitch from outside said service range to within said service range including a two part device having relatively movable parts and means operatively connected with said blades for relatively positioning said parts in accordance with propeller pitch, a first switch means for disabling said first electrical means, a second switch means for disabling said second electrical means and

means operatively connected with both said switch means and with said two part device and actuated thereby responsive to movement of said parts past a preselected relative position to effect actuation of both switch means to restore control to said governor.

6. In a controllable pitch propeller having a service range of pitch change and a special purpose range of pitch change beyond said service range, pitch changing mechanism, a governor for said mechanism for controlling the propeller pitch within said service range, a first manually controlled means connected with said mechanism for controlling the propeller pitch outside of said service range including means for disabling control by said governor, said pitch changing mechanism including a two part device having relatively movable parts and means for relatively positioning said parts in accordance with propeller pitch, control means operatively connected with said device and actuated thereby responsive to movement of said parts past a preselected relative position, means operatively connected with said first manually controlled means for disabling the same, means operatively connecting said control means with both of said disabling means to simultaneously automatically disable said first manually controlled means and restore control to said governor upon actuation of said control means.

7. In a controllable pitch propeller having a service range of pitch change and a special purpose range of pitch change beyond said service range, pitch changing mechanism including a two part device having relatively movable parts and means for adjusting the propeller pitch in accordance with the relative position of said parts, a governor operatively connected with said mechanism for controlling the propeller pitch within said service range, a first manually controlled means for moving the propeller into reverse pitch position, a second manually controlled means for disabling control by said governor, and a third manually controlled means for moving the propeller from reverse pitch into said service range, control means operatively connected with said device and actuated thereby responsive to movement of said parts past a pre-selected relative position in passing from reverse pitch position into said service range, means operatively connected with said third manually controlled means to disable the same, means operatively connecting said control means with both of said disabling means to simultaneously automatically disable said third manually controlled means and restore control to said governor upon actuation of said control means.

8. In a controllable pitch propeller having a service range of pitch change and a special purpose range of pitch change beyond said service range, pitch changing mechanism, a governor connected with said pitch changing means for controlling the propeller pitch within said service range, electrically actuated means connected with said pitch changing mechanism and said governor for controlling the propeller pitch outside of said service range including electrically actuated means for disabling control by said governor, means for automatically restoring control by said governor upon return of the propeller pitch from outside said service range to within said service range including a two part device having relatively movable parts and means connecting one of said parts with said pitch

changing mechanism for relatively positioning said parts in accordance with propeller pitch, a holding coil, switch means forming a part of the circuit of said electrically actuated means, an armature connecting said holding coil and said switch means for positioning said switch means to maintain control by said electrically actuated control means and maintain said governor disabling means effective, a second switch means forming a part of the electric circuit of said holding coil, means connecting said second switch means with said two part device for actuating said second switch means responsive to movement of said parts past a preselected position in returning to said service range from outside said service range to disable said electrical control means and restore control to said governor.

9. In a controllable pitch propeller having pitch changing mechanism and controls therefore, pitch limit stop means having cooperating relatively movable parts one of which parts is operatively connected with and movable with said pitch changing mechanism for limiting movement of said pitch changing mechanism, means operatively connecting said stop means and said controls for disabling said stop means, means operatively connected with said stop means and said pitch changing mechanism for automatically re-activating said stop means responsive to pitch changing movement of said pitch changing mechanism, a device connected with said stop means and with said controls and movable, by disabling movement of said stop means, into position to maintain a portion of said controls energized, means operatively connecting said device with said stop re-activating means for movement thereby, said device being movable by said re-activating means in its re-activating movement to de-energize said portion of said controls.

10. In combination with a propeller having controllable pitch blades, hydraulic means for controlling the pitch of the blades including a servo-motor, stop mechanism comprising high and low pitch limit stops connected with, and movable with, said pitch controlling means and a retractable stop normally biased into position between said limit stops and, with said limit stops, defining the constant speed range of the propeller blades, a constant speed governor controlling said servo-motor in said range, means automatically returning said retractable stop to said position upon return of said propeller blades to said range from beyond said range, said propeller blades having a special range beyond said constant speed range in which the blades are in reverse pitch, a first electrically actuated means connected with said governor and operative when energized to disable said governor, a second electrically actuated means connected with said servo-motor and operative when energized to control movement of said blades by said hydraulic means in returning said propeller blades from said special range to said governor controlled range and electrical means operatively connected with said cooperating stop mechanism and operated by the latter when said retractable stop returns to its normal position beyond said limit stops, means operatively connecting said electrical means and said electrically actuated means, said electrical means, when operated, de-energizing both said electrically actuated means to return said propeller to governor control.

11. In combination with a propeller having controllable pitch blades, hydraulic means for controlling the pitch of the blades including a

servo-motor, low pitch limit stop means having a portion operatively connected with said pitch controlling means and preventing movement of said servo-motor beyond a predetermined limit and dividing a constant speed range for the propeller blades from a reverse pitch range, a speed governor controlling said servo-motor in said constant speed range, electrically actuated means for disabling control by said speed governor, means for disabling said limit stop means, means for automatically re-activating said limit stop means upon return of said propeller blades to said constant speed range from said reverse pitch range, electrically actuated means controlling the movement of said blades by said hydraulic means in said return and switch means actuated by said low pitch limit stop means, means operatively connecting said switch means and both said electrically actuated means and means connected with said connecting means and effective upon actuation of said switch means by re-activation of said limit stop means to disable both of said electrically actuated means to return said propeller automatically to governor control when the propeller enters constant speed range from the reverse pitch range.

12. In a propeller system, a propeller having controllable pitch blades, and having a constant speed range and a reverse pitch range of pitch adjustment, hydraulic means for controlling the pitch of the blades including a pitch changing servo-motor operatively connected with said blades, low pitch limit stop means operatively connected with said pitch controlling means and preventing movement of said servo-motor beyond a predetermined limit and dividing the constant speed range for the propeller from the reverse pitch range, a speed governor operatively connected with said servo-motor in said constant speed range, means connected with said stop means for disabling said limit stop means to permit movement of said blades into reverse pitch range, electrically actuated means, connected with said servo-motor and said governor, controlling the movement of said blades by said hydraulic means in said reverse range, means operatively connected with said hydraulic means restoring said stop means upon return of said blades from reverse pitch range to constant speed range, and a switch actuated by said stop means and forming a part of the electrical circuit for said electrically actuated means for disabling said electrically actuated means and returning said propeller to governor control upon return of said blades to the constant speed range.

13. In a propeller system, a propeller having controllable pitch blades, hydraulic pitch controlling means for controlling the pitch of the blades including a pitch changing hydraulic motor, a distributing valve hydraulically connected with said motor for controlling said motor and a servo-motor connected with and controlling said valve, low pitch limit stops connected with, and movable with, said pitch controlling means, and a retractable stop engageable with said limit stop for limiting the pitch reducing movement of said servo-motor, means connected with said retractable stop for retracting said retractable stop to permit movement into reverse pitch, means holding said retractable stop retracted while the blades are in reverse pitch, a source of fluid under pressure, a speed governor connected with said source and said servo-motor and controlling the flow of said fluid to and from said servo-motor, a lock pitch solenoid valve connecting said governor and said servo-motor and when energized blocking flow be-

tween said governor and said servo-motor, an increase pitch solenoid valve connected with said servo-motor and when energized controlling fluid for moving said servo-motor toward high pitch, relay switch means connected with and controlling said solenoids, including a relay having a holding coil, contact means in the circuit for said holding coil and means operatively connected with said retractible stop releasably holding said contacts in closed position when said retractible stop is retracted and said propeller blades are in reverse pitch.

14. In a controllable pitch propeller having pitch changing mechanism and controls therefor, a mechanical pitch limit stop means operatively connected with said pitch changing mechanism for limiting the movement of said pitch changing mechanism, manually controlled means connected with said stop means for disabling said stop means, means connected with said pitch changing mechanism for automatically re-activating said stop means, control means operatively connected with said stop means and actuatable by

5 disabling and re-activating movement of said stop means, means connecting said control means and said controls to operate at least a portion of said controls, said controls including further means connected with said control means and actuated responsive to re-activating action of said stop to automatically de-energize at least a portion of said controls.

10 MELVIN E. LONGFELLOW.
